2 SHEETS—SHEET 2.

UNITED STATES PATENT OFFICE.

EMIL JAGENBERG, OF DUSSELDORF, GERMANY.

DEVICE FOR APPLYING ADHESIVE TO CARDBOARD SHEETS.

1,151,596.

Specification of Letters Patent. Patented Aug. 31, 1915.

Application filed August 25, 1914. Serial No. 858,424.

To all whom it may concern:

Be it known that I, EMIL JAGENBERG, a subject of the German Emperor, and a resident of 107 Himmelgeisterstrasse, Dusseldorf, Germany, manufacturer, have invented certain new and useful Improvements in Devices for Applying Adhesive to Cardboard Sheets, of which the following is a statement.

10 The known arrangements for applying adhesives to cardboard sheets show the disadvantage, that the applying plate will also be lowered when there is no sheet of cardboard beneath it, for instance, when 15 the mechanism for pulling the sheet from the pile has failed. The consequence will be that the plate, on which the cardboard sheets are advanced, is soiled with adhesive.

20 The present invention relates to an arrangement which will remove this disadvantage. This is obtained by a feeler situated in the path of the cardboard sheet being operated by the latter, when it has reached its position beneath the gumming plate, in 25 such a manner, that the said feeler will disengage a device locking the gumming plate.

20 In the accompanying drawing Figure 1 is a longitudinal section on the line A—B, and 30 Fig. 2 is a cross section on the line C—D through the arrangement.

35 The cardboard sheets which are pulled in known manner from the pile *a*, for example by means of endless rubber bands *o*, pass onto a table *c* and beneath the gumming plate *b*, which applies the adhesive to the parts where required. The gumming plate is fitted to a slide *e*, which is displaceably fitted to the rail *d*. The rail is secured to 40 the rods *f*, which are vertically displaceable in guides *p*. This raising and lowering of the rods *f* is effected by a cam disk *r*, against which bears the roller *s¹* of a double-armed lever *s*, which is coupled by a rod *g* with a 45 beam *h* carrying the rods *f*. The lowering of the gumming plate *b*, which is effected by means of springs *t*, can however only take place, when a hooked lever *i* has been disengaged from a nose *k* on the beam *h*. If this 50 lever *i* has not been thus disengaged, it will keep the beam *h* in raised position, even if the cam disk *r* should admit of the beam being lowered. The hooked lever *i* which is pivotally fitted on the pin *j* is coupled by

means of a link *m* to a curved feeler *n*, 55 which is journaled on the underside of the table *c* and when in raised position projects with its free, curved end through a slot *u* in the table *c*. When the feeler is in raised position (Figs. 1, 2), the hook *i* is 60 beneath the nose *k*, so that the gumming plate *b* cannot be lowered. When, however, a sheet of cardboard passes onto the table *c*, it depresses the feeler, whereby the hook *i* is lifted from the nose *k*, and the gear of 65 the gumming plate *b* is released. The gumming plate can, therefore, be lowered only when there is a sheet of cardboard beneath it on the table *c*, and depresses the feeler, thereby disengaging the hook. 70

For the purpose of facilitating the movement of the feeler *n*, an arm *v* is attached to the lever *i*, on which an adjustable weight *v¹* is fitted. By displacing this weight the force with which the feeler is raised, may be 75 adjusted at will.

On the slide *e* is provided a pin, *w*, which is coupled by means of a rod *x* with a lever *y*. This lever is rocked to and fro by means of a cam disk *z* and a forked rod *l*, whereby 80 the gumming plate *b* is reciprocated on the rail *d*. During such travel the gumming plate comes into contact with the continuously revolving roller *q*, by which it is provided with adhesive. 85

I claim:

1. A device for applying adhesive to sheets, comprising a table adapted to support a sheet, a rail above the table, a gumming plate movable on the rail, means for lowering the rail, a feeler extending above the table, and means controlled by the feeler, for locking the rail-lowering means. 90

2. A device for applying adhesive to sheets, comprising a table adapted to support a sheet, a rail above the table, a gumming plate carried by the rail, cam-actuated rods engaging the rail, a beam engaged by the rods, a feeler extending above the table, and a hook actuated by said feeler 100 and adapted to engage the beam.

In testimony whereof I have hereunto set my signature in the presence of two subscribing witnesses.
